INVENTOR.

UNITED STATES PATENT OFFICE.

JOHN W. KLINE, OF WHITE HAVEN, PENNSYLVANIA.

WRENCH.

No. 873,758.

Specification of Letters Patent.

Patented Dec. 17, 1907.

Application filed April 25, 1907. Serial No. 370,244.

To all whom it may concern:

Be it known that I, JOHN W. KLINE, a citizen of the United States, residing at White Haven, in the county of Luzerne and State of Pennsylvania, have invented a new and useful Wrench, of which the following is a specification.

This invention relates to a wrench of that type known as "monkey" wrenches, in which a straight stem or stock is provided with a fixed jaw and a movable jaw slideable on said stem to adjust the wrench for grasping articles of various sizes.

The object of this invention is to provide in combination a wrench having jaws for turning articles of polygonal section such as bolts and nuts, and separate jaws for rotating those that have a circular section, pipes and rods, for instance, the movable jaws in both cases formed on or attached to a unitary frame.

Another object of the invention is to provide a simple and quickly acting mechanism for disconnecting the unitary movable jaws from the shank so that they can slide freely thereon to any position desired, then applied to the article to be turned, roughly adjusted and locked in place and finally set by the usual worm or screw common to wrenches of this class.

With these and other objects in view, the invention consists of the novel construction, combination and arrangement of parts hereinafter described and definitely claimed.

In the accompanying drawings:—Figure 1 is an elevation of the improved wrench. Fig. 2 is a similar view partly in section. Fig. 3 is a horizontal section on the line 3—3 of Fig. 1.

Similar numerals of reference indicate the same parts on all the figures.

The stock 1 is a straight rectangular bar of metal provided on one side with a series of teeth 2 near one end, to which end a head 3 is attached or formed integrally therewith. The head 3 preferably extends laterally beyond the stock on opposite sides thereof as indicated by 4 and 5. The under face 6 of the extension 4 is flat and perpendicular to the stock 1, said extension forming the fixed jaw of the wrench for operating on polygonal articles. The opposite extension or jaw 5 is concaved on its under side and provided with teeth 7 which bite on and hold cylindrical articles to be rotated.

The unitary movable jaw frame 8 is adapt-

ed to slide freely on the shank 1, but may be locked thereto in such manner that it can only move by rotating the screw or worm 9 which engages the teeth 2 on one side of the stock. On the movable jaw frame 8 under the fixed jaw 4 is a jaw 10 having a flat face 11 adapted to coöperate with the face 6 of the fixed jaw. A jaw 12 having a convex face in opposition to the concave face of the fixed jaw 5 is pivoted to the jaw frame 8 opposite the jaw 10, and has teeth 13 similar to the teeth 7.

The jaw frame 8 is cut away at 14 below the pivoted jaw to permit it for one purpose to swing and disengage the worm 9 from the teeth 2. Below the jaw 10 the jaw frame 8 is cut away to form a rectangular notch in which is seated the worm 9 pivoted on the smooth upper end of a screw 15 threaded in the extension 16 of the jaw frame below the notch. A companion extension 17 projects from the movable jaw frame 8 on the opposite side of the shank 1 and is made hollow with an inclined outer wall for the admission of the bolt or wedge 18 which also has a side of the same inclination as said outer wall and when in place is in contact with it. The lower part of the wedge or bolt 18 is curved outwardly to form an operating end or hook 19 for sliding it, and on its inner side or side next the shank 1 is a thin strip of metal 20 preferably steel, extending above the wedge or bolt, to which is attached at its end a block 21 projecting outwardly for a short distance. Fastened to the outer side of the block 21 is a flat spring 22 its upper part parallel to the strip 20 for a short distance, and is then bent into an offset 23 just above the extension 17, to form a stop. Continuing downwardly from the offset 23 but at an angle, the spring lies in a slot 24 on the outer inclined face of the extension 17, and finally terminates with a slight inwardly curved end 25 above the hook shaped end 19.

When it is desired to move the jaw frame 8, a finger of the hand is placed below the curved end 25, and the spring 22 lifted until the offset 23 is drawn over the upper edge of the extension 17, as indicated by dotted lines in Fig. 2. The bolt or wedge 18 is then drawn downwardly, carrying the spring 22 with it, and the latter being under tension, forces the jaw frame 8 to tilt to one side, freeing the worm 9 from the teeth 2. The jaw frame can now be moved freely up and down the stock at will, and so soon as the desired position has

been reached, it will only be necessary to push the bolt or wedge into the opening in the extension 17 sufficiently far to let the offset snap into place over the extension. 5 A finer adjustment of the jaws is obtained in the usual manner by rotating the worm 9 which is in engagement with the teeth 2.

The movable jaw 12 has sufficient independent movement on its pivot to clamp a 10 pipe or other cylindrical object when placed between it and the fixed jaw 5.

Having thus described the invention, what is claimed is:—

1. A wrench of the class described having 15 a shank and a jaw frame movable thereon, a projection on said jaw-frame having a socket with an inclined wall, a wedge fitted to said socket and adapted to bear against said shank and said inclined wall, and a 20 spring attached to said wedge to lock it in place in said socket and to tilt said jaw frame and hold it in tilted position when unlocked and the wedge withdrawn.

2. A wrench of the class described having 25 a toothed shank, a jaw frame movable thereon and carrying a rotatable worm or screw adapted to engage the teeth in said shank, a projection on said jaw-frame opposite the side carrying the worm and having an inclined outer face and an interior through- 30 socket with a wall parallel to said outer face, a wedge bolt fitted to said socket having a forwardly projecting strip, and a spring fastened to the end of said strip and extending 35 over the outer face of said projection with a tensional bearing thereon.

3. A wrench of the class described having 40 a toothed shank, a jaw-frame movable thereon and carrying a rotatable worm or screw adapted to engage the teeth in said shank, a projection on said jaw-frame on the side opposite that carrying the worm or screw 45 having an inclined slot in its outer face and an interior through socket with a wall parallel to said inclined slot, a wedge bolt fitted to

said socket and having a forwardly projecting strip and a rearwardly extending operating end, and a spring fastened at the extreme end only of said strip and lying in the exterior slot on said projection with a tensional bearing, said spring having an offset set for locking the wedge in its socket to prevent the jaw tilting. 50

4. A wrench of the class described having a toothed shank, two fixed jaws and two co-operating movable jaws on a tiltable jaw frame, means for engaging said teeth to move said jaw frame longitudinally of the shank, a projection on the side of said jaw frame opposite the moving means having a socket 60 with an inclined wall, a wedge bolt fitted to said socket and having a forwardly projecting strip, and a spring fastened to the end of said strip and arranged to press said projection against the wedge which latter when 65 withdrawn from its socket permits the spring to tilt said jaw frame and disconnect said longitudinally moving means.

5. A wrench of the class described having a tiltable jaw frame and means for moving 70 it longitudinally on the shank, a projection having a socket with an inclined wall, a wedge fitted to said socket provided with a forwardly extending strip, and a spring fastened to the end of said strip extending 75 outside said projection and having an offset adapted to lock over the projection and hold the wedge in place and the jaw against tilting, but when the spring is disengaged from said projection, the wedge may be withdrawn 80 from its socket causing said spring to bear on said projection and tilt the jaw frame to disengage the longitudinally moving means.

In testimony that I claim the foregoing as my own, I have hereto affixed my signature in the presence of two witnesses.

JOHN W. KLINE.
